UNITED STATES PATENT OFFICE.

JOHN H. DEAN, OF BIRMINGHAM, ALABAMA.

SHEET-METAL CULVERT.

Specification of Letters Patent. Patented Dec. 2, 1913.

1,080,329.

Application filed January 16, 1913. Serial No. 742,420.

To all whom it may concern:

Be it known that I, JOHN H. DEAN, a citizen of the United States, residing at Birmingham, in the county of Jefferson and State of Alabama, have invented certain new and useful Improvements in Sheet-Metal Culverts, of which the following is a specification, reference being had therein to the accompanying drawing.

10 This invention relates to sheet metal culverts or pipes to be used as drains, aqueducts or the like, and more particularly to such culverts of the butt-joint type particularly set forth and covered in Patent No. 15 1,049,816, granted to John H. Dean, on January 7, 1913, wherein the same are built of sections adapted to be knocked down and nested together in shipment and storage and to be set up and formed into a complete cul- 20 vert or pipe at the place where the same is to be used.

It is the object of this invention to provide a culvert which is made up of corrugated metal sections, preferably half sections, one 25 of said sections having rigid metal strips or bars welded or riveted to the same at or near its longitudinal edges, and the other of said sections carrying keys or clips spaced at intervals along the sides of said sections and 30 projecting beyond the longitudinal edges thereof, so that when the sections are placed together with their longitudinal edges meeting, the said keys or clips of one section are adapted to engage with the strips or bars of 35 the other section for holding and retaining said sections in connected relation with their longitudinal edges in true abutting relation. In connection with this object of the invention, it is to be noted that the rigid strips or 40 bars carried by one of the sections are directly connected to the convex corrugations of said section, in which event spaces or passageways are formed between the concave corrugations of said section and the metal 45 strips, and that the keys or clips of the other complementary section are secured to the concave corrugations of said section, so that they are in proper position to engage within the passageways above referred to, 50 when said complementary sections are placed in proper assembled relation.

I have illustrated my invention in the accompanying drawing, in which—

55 Figure 1 is a side elevation of a portion of a culvert showing the sections of the same constructed in accordance with my in-

vention and in connected relation one with the other, Fig. 2 is a transverse sectional view of the culvert taken on the line 2—2 of Fig. 1, Fig. 3 is a side elevation of one of the keys or clips which are adapted to be carried by one of the complementary sections, and Fig. 4 is a perspective view of said key.

Referring to the drawings, the complementary sections indicated at 1 are provided with corrugations which are arranged parallel with opposite ends thereof; and these sections which are preferably half sections, are adapted, when arranged in assembled position to form a completed culvert, to have the corrugations of upper and lower sections coincide with each other, or in other words, to have each convex and concave corrugation of an upper section directly in line with the convex and concave corrugations respectively of the section below it. The sections are constructed without any outstanding flanges, and are adapted to have the longitudinal edges of complementary sections abut as indicated at 2, so that when the sections are connected together with their longitudinal edges meeting or abutting, the corrugated culvert, for all intents and purposes, has the appearance 85 and strength of an integral corrugated cylinder.

As clearly shown in the drawing, the upper section 1 is provided at or near its longitudinal edges, with rigid strips 3—3, 90 which are secured to the convex corrugations of said section, preferably by welding or riveting the same thereto, and it will be noted that passageways, as indicated at 4, 95 are formed between the sides of this corrugated culvert section and the said metal strips at points intermediate the convex corrugations of said section.

The lower complementary section carries along its longitudinal edges metal keys or 100 clips 5, which are spaced at any desired interval, and are adapted to be secured to the sides of said culvert section, preferably by welding or riveting the same to the concave corrugations of said section at the points 105 indicated at 6. These keys or clips are curved transversely to conform to the curvature of the concave corrugations of said culvert, and the same project some distance from the longitudinal edges of the lower 110 section, and are thus adapted to be inserted within the passageways formed between the

sides of the upper culvert section and the metal strips 3 above referred to. It is to be noted that these keys neatly fit within the passageways 4 and thus serve to correctly position the abutting longitudinal edges of complementary sections, and furthermore to retain said edges in such abutting relation. The keys are furthermore provided at their free end with fingers 7-7 which, if found necessary, are adapted to be bent over into engagement with the upper edge of the metal strips 3, for the purpose of firmly holding the complementary sections in connected relation.

15 It has been found in certain sizes of culverts that it is not necessary to bend over the fingers 7-7 into engagement with the upper edge of the strips 3 for the purpose of tying or holding complementary sections in connected relation, but that the mere insertion of the keys within the passageways is quite sufficient, and this due to the frictional engagement between said keys and the sides of the culvert section and strips.

20 Many advantages are obtained by a construction of sheet metal culvert along the lines as herein specified, it being noted that all of the various parts of the fastening means for connecting together complementary sections are permanently carried by the sections themselves, which has its obvious advantages.

Having thus described my invention, what I claim and desire to secure by Letters Patent is:-

1. A sheet metal culvert comprising complementary corrugated sections having longitudinal abutting edges, a metal strip or bar secured to the convex corrugations of one of said sections thereby forming a space or passageway between each concave corrugation of said section and the metal strip, and fastening means rigidly and permanently secured to the other of said sections and adapted for engagement within the passageways referred to for holding and retaining the longitudinal meeting edges of said sections in abutting relation and fastening the sections together.

2. A sheet metal culvert comprising complementary sections having longitudinal abutting edges, a metal strip or bar secured to said section along the longitudinal edge thereof, said strip being so formed as to leave a space or passageway at intervals between the culvert and the strip, and fastening means rigidly and permanently secured to the other of said sections along the longitudinal edge thereof and adapted for insertion within said passageways to correctly position the abutting longitudinal edges and furthermore to hold said edges in connected relation.

position the longitudinal edges of the complementary sections and furthermore to hold said sections in connected relation.

3. A sheet metal culvert comprising complementary corrugated sections having longitudinal abutting edges, a metal strip or bar secured to the convex corrugations of said section along the longitudinal edge thereof, and a key or clip rigidly and permanently secured to the concave corrugation of the other of said sections and adapted to engage within a passageway formed between a concave corrugation of the first mentioned section and the metal strip secured thereto.

4. A sheet metal culvert comprising complementary corrugated sections having longitudinal abutting edges, a metal strip or bar secured to the convex corrugations of said section along the longitudinal edge thereof, and a key or clip rigidly and permanently secured to a concave corrugation of the other section, said key or clip being transversely curved to conform to the curvature of the concave corrugations of said sections and adapted to engage within a passageway formed between a concave corrugation of the first mentioned section and the metal strip.

5. A sheet metal culvert having longitudinal abutting edges, a metal strip or bar secured to said culvert along one of its longitudinal edges, said strip being so formed as to leave a space or passageway at intervals between the culvert and the strip, and fastening means rigidly and permanently secured to the culvert along another of its longitudinal edges and adapted for insertion within said passageways to correctly position the abutting longitudinal edges and furthermore to hold said edges in connected relation.

6. A sheet metal culvert having longitudinal abutting edges, a metal strip or bar secured to said culvert along one of its longitudinal edges, said strip being so formed as to leave a space or passageway at intervals between the culvert and the strip, and a key or clip rigidly and permanently secured to the culvert along another of its longitudinal edges and adapted for insertion within said passageways to correctly position the abutting longitudinal edges and furthermore to hold said edges in connected relation.

In testimony whereof I have affixed my signature in presence of two witnesses.

JOHN H. DEAN.
